US00D940757S

(12) **United States Design Patent** (10) **Patent No.:** **US D940,757 S**
Rondoni et al. (45) **Date of Patent:** **** Jan. 11, 2022**

(54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **John Rondoni**, Plymouth, MN (US); **David Dieken**, Minneapolis, MN (US); **Maria Isabel Ancona**, Boston, MA (US)

(73) Assignee: **INSPIRE MEDICAL SYSTEMS, INC.**, Golden Valley, MN (US)

(**) Term: **15 Years**

(21) Appl. No.: **29/754,782**

(22) Filed: **Oct. 14, 2020**

Related U.S. Application Data

(63) Continuation of application No. 29/716,484, filed on Dec. 10, 2019, now Pat. No. Des. 914,044, which is a continuation of application No. 29/649,586, filed on May 31, 2018, now Pat. No. Des. 869,490.

CLAIM

We claim the ornamental design for a display screen or portion thereof with a graphical user interface, as shown and described.

DESCRIPTION

The single FIGURE is a front view of a display screen or portion thereof with a graphical user interface showing our new design.

The outermost broken line showing the display screen or portion thereof and all other broken lines showing portions of the graphical user interface are included for the purpose of illustrating portions of the article and form no part of the claimed design.

1 Claim, 1 Drawing Sheet
